UNITED STATES PATENT OFFICE.

JAMES ALTON MORRISON, OF MACDOEL, CALIFORNIA.

MARINE PROPULSION APPARATUS.

Application filed April 12, 1924. Serial No. 706,060.

To all whom it may concern:

Be it known that I, JAMES ALTON MORRISON, a citizen of the United States, residing at Macdoel, in the county of Siskiyou and State of California, have invented certain new and useful Improvements in Marine Propulsion Apparatus, of which the following is a specification, reference being had to the accompanying drawings.

10 This invention relates to marine propulsion apparatus and more particularly to an improved propeller construction.

An important object of the invention is to provide a propeller of the paddle-wheel type the blades of which are so constructed that they engage the water with maximum propulsion efficiency, these blades being supported by arms constructed to allow relative movement of the blades with relation to the 20 shaft from which they are driven, the blades themselves being weighted so that the arms by which they are supported are normally held radial to the shaft by centrifugal force. This type of mounting of the blades permits yielding of the blades at the point of initial contact with the water or at that point which in a rotating paddle-wheel blade serves in the ordinary construction not to cause the boat to progress but to elevate in 25 the water.

A further object of the invention is to provide a novel mounting for the drive shafts of propellers of the paddle-wheel type so that the depth of submergence of the 30 blades may be regulated.

These and other objects I attain by the construction shown in the accompanying drawings, wherein for the purpose of illustration is shown a preferred embodiment 40 of my invention and wherein:

Figure 1 is a vertical sectional view through a hull showing propellers and driving apparatus for the propellers constructed in accordance with my invention;

45 Figure 2 is a detail sectional view through the end of the drive shaft mounting and the adjacent portions of the propeller;

Figure 3 is a vertical section taken through the propeller shaft bearing adjacent the 50 inner face of the hull;

Figure 4 is a plan view showing the mounting of the propeller bearings upon the wall of the hull;

55 Figure 5 is a sectional view showing the construction of the center bearing;

Figure 6 is a sectional view through the

hub of the propeller showing the oil passages;

Figure 7 is an enlarged detail view showing one form of construction of the blades 60 of the propeller;

Figure 8 illustrates a modified propeller construction in which the arms bearing the blades or paddles are flexible.

Referring now more particularly to the 65 drawings, the propeller comprises a hub portion 10 from which radiate arms 11 the outer ends of which are provided with blades or paddles 12. The blades or paddles each consist of a very heavy body the active face 70 of which is cupped, as indicated at 13. The arms 11 may be either of the type shown in Figure 1 or 8. In the first figure each arm is formed in two sections one of which, indicated at 14, is rigidly secured to the hub 75 and the other of which, indicated at 15, is secured to the blade 12. These arms are provided with a pivot permitting relative movement of the section 15 to the section 14 in the general plane of rotation of the arms. 80 In this type of construction the hub is preferably provided with an oil chamber 16 communicating with ports 17 extending longitudinally of the sections 14 to the pivotal connection so that oil may be delivered to 85 these connections to prevent undue wear and insure freedom of movement of the sections 15 at all times. In the form shown in Figure 8 the arms 11 are flexible so that they may yield to permit a change in angle between the active face 13 of the blades 12 and the shaft engaging portion of the arm.

In Figure 1 I have illustrated a preferred form of mounting for propellers of this construction. In the opposite side walls of the 95 vessel vertical slots 18 are formed. Upon the interior of the vessel at opposite sides of these slots vertical guides 19 are secured in which are engaged the side edges of vertically adjustable plates 23. In the present 100 instance, as a means for adjustment of the plates I have shown the lower ends of the plates as provided with a worm-threaded extension 24 which extends into a standard 105 arranged upon the deck of the boat. The upper end of this base forms a support for a pair of nuts 27 mounted upon the worm-threaded extension, one of which serves as a lock nut while the other serves to regulate raising or lowering of the plate 23 by the 110 extension. These plates 23 have bearings 28 for the ends of a shaft 29, these bearings pro-

truding through the slots 18. The shaft, if desired, may be provided intermediate the bearings 28 with additional vertically adjustable bearings 30. In the present instance I have shown one of these bearings, the bearing having at its lower end a vertically extending plate 31 operating through a guide 32 carried by standards 33. The lower end of this plate is provided with an extension 24^a similar to the extension 24 of the plates 23 and has arranged therebeneath an adjusting mechanism including parts 25^a, 26^a and 27^a similar to the parts 25, 26 and 27 employed for adjusting the plates 23. This shaft may be provided with a crank 34 for connection with a drive or may be driven in any suitable manner.

The shaft preferably has extended longitudinally thereof an oil feed port 35 fed from oil cups 36 carried by the bearings 28 and 30. The outer ends of the shafts are provided with squared shanks entering the sockets of the hubs 10 of the propellers and through one side face of the squared shank 37 this port opens for communication with the oil pocket 16 of the propeller hub. This lubrication is provided not only for the bearings of the shaft proper but for the bearings of the blade arms if these are jointed. In the operation of the device the blade is swung outwardly by centrifugal force and upon striking the water the momentum of the blade is retarded and this retardation of the blade is transferred to the vessel resulting in forward motion thereof. Due to the fact that the blades may change their angle to the point of attachment of the arms to the shaft, the tendency to upward thrust by the blades is eliminated and the efficiency of the blades of propulsion increased. By varying the depth of engagement of the blades through vertical adjustment of the shaft 29, the speed of propulsion may be regulated through regulation of the period of engagement of the blades with the water and the depth of such engagement. It will, of course, be understood that the shaft 29 must be rotated at a considerable speed at all times in order that the weighted blades may assume their proper positions between the times when they leave the water

and when they again enter the same. It will, of course, be obvious that the construction of the propeller as hereinbefore set forth is capable of a considerable range of change and modification without materially departing from the spirit of my invention and I accordingly do not limit myself to such specific structure except as hereinafter claimed.

I claim:—

1. In a propeller of the paddle-wheel type, a hub, arms radiating from the hub, blades carried by the outer ends of said arms, said blades being of considerable weight, said arms including blade attached and hub attached portions capable of angular movement with relation to one another in the line of swing of the blades.

2. In a propeller of the paddle-wheel type, a hub, arms radiating from the hub, blades carried by the outer ends of said arms, said blades being of considerable weight, said arms including blade attached and hub attached portions capable of angular movement with relation to one another in the line of swing of the blades, and a hinged connection between said portions.

3. In a propeller of the paddle-wheel type, a hub, arms radiating from the hub, blades carried by the outer ends of said arms, said blades being of considerable weight, said arms including blade attached and hub attached portions capable of angular movement with relation to one another in the line of swing of the blades, a hinged connection between said portions, and means feeding a lubricant from the hub to said hinged connections.

4. In a propeller of the paddle-wheel type, a hub, arms radiating from the hub, blades carried by the outer ends of said arms, said blades being of considerable weight, said arms including blade attached and hub attached portions capable of angular movement with relation to one another in the line of swing of the blades, the connection between said portions being flexible.

In testimony whereof I hereunto affix my signature.

JAMES ALTON MORRISON
